INVENTOR:

Charles Mahan

United States Patent Office.

CHARLES MAHAN, OF GRAND ISLAND, CALIFORNIA.

Letters Patent No. 77,500, dated May 5, 1868.

IMPROVEMENT IN FARM-WAGON.

The Schedule referred to in these Letters Patent and making part of the same.

TO ALL WHOM IT MAY CONCERN:

Be it known that I, CHARLES MAHAN, of Grand Island, in the county of Colusa, and State of California, have invented certain new and useful Improvements in Farm-Wagons; and I do hereby declare that the following is a full and complete description of the same, reference being had to the accompanying drawings, making part of this specification, in which—

Figure 1 is a side view of the wagon.

Figure 2 is a view of the top.

Figure 3, a top view of the carriage.

Figure 4, an end view of fig. 1.

Figure 5, a modification of fig. 1.

Figure 6, a top view of fig. 5.

Figure 7, a detached view of the body of the wagon.

Like letters of reference refer to like parts in the different views presented.

Fig. 1 represents the wagon, of which A is the box or body, and B the carriage. This carriage consists of the wheels C, axles D, front and rear pillows E E', all of which are, or may be, constructed in the ordinary way.

It will be observed that the hounds F, fig. 3, are placed in front of the axle-tree instead of behind it, as is done in the ordinary wagon, and that the sway-bar, G, is also in front. By thus arranging the hounds and sway-bar in front, the carriage, by removing the box, can be used as an ordinary truck for drawing logs, timber, &c. The hounds not being in the way of loading them, it is at once a most convenient vehicle for this purpose.

Fig. 5 is a modification of this wagon, and is represented as an ox-cart for general farm-use. This conversion is made by simply detaching the front wheels from the carriage, leaving the reach, H, still attached to the hind wheels. This reach is intended to be made of sufficient length to serve as the tongue to which the cattle are yoked for draught. The body or box I is secured to the wheels by means of a frame, consisting of the cross-pieces J J' and centre rail K, fig. 5. To the cross-piece J is hinged the box, as seen at a, so that it can be tipped from the position indicated by the dotted lines b, to that shown in the drawing, for the purpose of discharging the load.

The box, when in a horizontal position, as indicated by the dotted lines, is thus secured by the slide-hook A', fig. 6. The curved arm a', on changing the position of the hook from that shown in fig. 4, is forced under the pin c, the curve and shape of the arm being such as to draw the box down tightly upon the frame, and thereby holds it securely in place. By this change and rearrangement of the wagon, is obtained a convenient cart, with little expense, time, and labor, as the running-gear is furnished from the wagon, shown in fig. 1.

The body or box of the wagon, represented in fig. 1, is so constructed that its sides and ends can be taken off, and leaving only the bottom as a platform or bed, as indicated by the dotted lines c, fig. 2, consisting of a central plank, B', and side rails, c', which, by the addition of side stakes, is well adapted to drawing cord-wood. It being made to a certain size, the wood is measured thereby.

The peculiar manner in which the box A referred to is put together is as follows: To the ends of each side, and at the middle, are fixed brackets or cleats, C', fig. 7, in the edge of which is cut a notch, b: These notches, when the sides are put in position, are lodged on the inner upper corner of the rail, which prevents them from falling down or being drawn upward. The sides are kept apart by the end-boards, and to which they are secured by the springs, e, fastened to the edge of the boards, and the hook sprung down on the outside of the sides, as shown in fig. 4.

The front end-board is a fixture, whereas the tail-board is made so that it can be removed, but which is held in place by a slide-hook similar to that above described. By this construction and arrangement of the box it is readily and easily taken off or put on the carriage, so that the entire structure is one of great convenience and utility.

What I claim as my improvement, and desire to secure by Letters Patent, is—

1. The frame, consisting of the cross-pieces J J' and central rail K, as arranged, in combination with the box I, axle-tree D, wheels C, and reach H, in the manner and for the purpose substantially as set forth.
2. The sliding hook A', when constructed in the manner and for the purpose specified.
3. The box A, when the sides of said box are provided with cleats C', notches b, and spring-catches e, in the manner and for the purpose set forth.

CHARLES MAHAN.
